US00D528100S

(12) **United States Design Patent** (10) **Patent No.:** **US D528,100 S**
(45) **Date of Patent:** **** Sep. 12, 2006**

(54) **DISC PLAYER**

(75) Inventor: **Satoshi Suzuki**, Tokyo (JP)

(73) Assignee: **Sony Corporation**, Tokyo (JP)

(**) Term: **14 Years**

(21) Appl. No.: **29/231,507**

(22) Filed: **Jun. 7, 2005**

(30) **Foreign Application Priority Data**

Mar. 4, 2005 (JP) D2005-006385

(51) **LOC (8) Cl.** **14-01**

(52) **U.S. Cl.** **D14/156**

(58) **Field of Classification Search** D14/156-157,

D14/160-165, 167-168, 192, 217; 360/99.02,

360/99.07; 369/75.11, 75.21, 77.21, 77.11;

720/612, 619, 647, 655; 455/344, 347-351

See application file for complete search history.
